TUBE-MILL.

1,204,554.

Specification of Letters Patent. Patented Nov. 14, 1916.

Application filed April 28, 1915. Serial No. 24,437.

To all whom it may concern:

Be it known that I, JOHAN S. FASTING, a subject of the King of Denmark, residing in Frederiksberg, near Copenhagen, Denmark, have invented certain new and useful Improvements in Tube-Mills, of which the following is a specification, reference being had to the accompanying drawings, forming a part hereof.

10 This invention relates to tube mills with continuous feed and discharge, and charged with free grinding bodies. In mills of this general character, there is always a slippage between the charge and the mill when the 15 mill is rotated, which slippage reduces the efficiency of the machine. In mills with comparatively smooth linings and operating at moderate speeds the slippage has generally been reduced by increasing the charge 20 in the mill. This method, however, has the disadvantage that the weight on the bearings is materially increased, thus increasing also the friction losses and increasing the power required to operate the mill, and it 25 has the further disadvantage that the wear on the grinding bodies is very high owing to the heavy charge in proportion to the output. It has been attempted to reduce the charge and secure proper lifting action in 30 the mill by means of longitudinal ribs or bars or by steps on the lining such as corrugations, and also by projections on the lining or dents or depressions in it, which would help to lift the charge in the mill to 35 the proper point. This method suffers from the disadvantage that it throws and tumbles the grinding bodies among one another in an irregular manner which, in accordance with past experience, tends to reduce the 40 grinding efficiency of the machine. In later practice it has been attempted to reduce this slippage by increasing the speed of the machine, and in this manner to make use of the increased centrifugal force to lift the 45 grinding bodies up to the proper point. This results in a more efficient grinding action than is obtained in mills of the first mentioned class, particularly by the lifting of the grinding bodies to a point very close to 50 the zenith of the mill and the throwing of

them across the grinding drum in a continuous stream, with the material, against the opposite side of the machine, and thereby materially increasing the efficiency of the apparatus. The higher speed of the drum in 55 this case, however, naturally will increase the friction losses in the main bearings and the wear on the operating gear as well as the power to operate the mill.

The object of the present invention is to 60 overcome these disadvantages by employing other means to carry the grinding bodies up to the proper point than by increasing the charge or the centrifugal force, or by employing longitudinal bars or projecting knobs 65 or pockets to throw and toss the grinding bodies about in the mill, and thus by decreasing the charge of grinding bodies and avoiding very high speed to decrease the 70 friction losses as well as the wear of the grinding bodies.

The present invention further has as its object to cause the grinding bodies to operate in the most efficient manner in the mill by lifting them up to the proper point 75 and causing them to move in a continuous stream, together with the material, down over the ascending mass of grinding bodies and material toward the bottom of the mill.

To accomplish this there are introduced 80 into the mill members which increase the frictional drag between the mass of the grinding bodies and the mill in a direction parallel to the path of the ascending grinding bodies, and tend to lift the grinding 85 bodies to a sufficient height, and there release them so that they shall move continually in a solid transverse stream and be caused to grind the material without being tossed about in the mill in various directions in the manner described above and by methods which have proved inefficient. The frictional members introduced into the machine for this purpose consist of laterally 90 or transversely disposed ribs, or flanges, or partitions, either continuous or interrupted, and these mechanical devices, while performing their intended function, are not of a character to interfere with the normal 95 operation of the mill or to prevent its most 100

efficient operation either with respect to the travel of the material through the mill or with respect to the steady and uniform grinding of the material. In fact it has 5 been shown that the improved mill possesses certain advantages in practice which are not to be obtained under all conditions of use by the old method of securing the hammering action as in mills of the second class as mentioned above.

Structurally the improved mill is of the usual form save that several circumferential ribs or flanges, either continuous or interrupted, are disposed on its inner wall in 15 planes at right angles to the axis of the mill to form partitions to separate the grinding bodies and material into parallel, transverse streams. These ribs or flanges or partitions are so disposed with respect to each other 20 that the grinding bodies and material between them, besides the frictional support afforded by the shell, also receive a frictional support laterally against the ribs or flanges or partitions, so as, either by a 25 bridging or arching action or by an increased frictional drag, materially to increase the slippage between the charge and the mill. The flanges or ribs or partitions may be made still further to increase the grip or 30 frictional drag between the engaged grinding bodies and material and the mill and yet permit the free movement of the material longitudinally through the mill, as by perforating the partitions or forming each as an 35 interrupted circumferential series of detached or separated plates or blades.

The ribs or flanges or partitions are preferably made relatively thin, so as to cause 40 as little disturbance to the natural motion of the grinding bodies as possible, and preferably with large lateral faces against which the grinding bodies and material rest, so as to increase as much as possible the frictional grip or drag between the mill and the charge 45 of grinding bodies and material, and also at the same time to increase the total surface of the mill with which the grinding bodies come in contact, as this also tends to increase the efficiency of the apparatus. The 50 preferred forms of the ribs and flanges and the relative dispositions thereof with respect to each other to effect the desired results, will appear more particularly hereinafter as the description proceeds, reference now being 55 had to the accompanying drawings for a detailed description, in which—

Figure 1 is a view in longitudinal section of the mill embodying the present invention. Fig. 2 is a view in transverse section taken 60 through the mill shown in Fig. 1. Fig. 3 is a view in transverse section of a mill provided with internal ribs or partitions of slightly modified form. Fig. 4 is a view in longitudinal section of the mill illustrated

in Fig. 3. Fig. 5 is a view in transverse section taken through a mill provided with still another form of internal flanges or partitions, and Fig. 6, is a longitudinal section of the mill illustrated in Fig. 5.

The mill *a* shown in the drawings may be 70 of usual form and be capable of operation under the usual conditions and speed of grinding. On the inner wall of the mill there are provided, in the embodiment shown in Figs. 1 and 2, several circumferential series of relatively thin transverse plates or flanges *b*, spaced from each other to divide the mill, adjacent the circumferential wall, 75 into circumferential channels. The plates of one series are set so as to lap the spaces between the plates of the next series to facilitate the travel of the material longitudinally through the mill. These plates or flanges *b* are disposed at right angles with respect to the axis of the mill, and extend inwardly 80 from the wall of the mill for a suitable distance to divide the mass of grinding bodies and material, into parallel transverse streams and create frictional drag between the mass 85 and the mill forming annular channels, but 90 it will be understood that the radial extension of the plates may be varied so as to give the greatest possible effect in reducing slippage and lifting the charge. The gist of the invention resides in the provision of the 95 flanges or plates or ribs *b*, or the equivalents thereof, to form partitions to separate the material and grinding bodies into parallel transverse streams and thereby increase the area of contact between the moving parts of 100 the mill and the mass of material and grinding bodies. The partitions may be placed at such distances from each other that the material and grinding bodies (indicated by the shading in the figures) shall bridge or arch 105 the space between the proximate ribs, so as to be carried up with the wall of the mill, as the latter rotates, to a point near the zenith where the material and the grinding bodies will leave the wall of the mill and fall upon 110 the material at the bottom, in parallel transverse streams, or the partitions may be at such distances that there shall be only a substantial reduction of slippage with no 115 bridging action. Of course, the speed of rotation of the mill will be such as to tend to carry the grinding bodies and the material part of the way up from the lowest point to the highest, but the resulting centrifugal force at the preferred speed, is not sufficient 120 to carry the charge of material and grinding bodies up to a point where the most efficient grinding action will ensue when gravity prevails. Such lifting is accomplished, at comparatively low speed, by the increased frictional drag afforded by the circumferential partitions. It will be noted from Fig. 2 that 125 the longitudinal movement of the material

through the mill is not interfered with because of the spaces between the plates *b* in each circumferential series.

In the embodiment illustrated in Figs. 3 and 4, circumferential annularly arranged and extended ribs *B* are employed, and each rib is spaced from one another circumferentially to form a series of openings *c*, which enhance the frictional drag and also 10 permit the material to pass freely in its longitudinal movement through the mill. The spacing of the ribs *B* with respect to each other may be as described with respect to Figs. 1 and 2, such that the grinding 15 bodies and the material will bridge or arch between the ribs and thereby be carried up with the wall of the mill nearly to the zenith, where the material and grinding bodies under the influence of gravity will 20 fall toward the lower part of the mill, or such that they will act frictionally on the material, without causing a bridging action, and so cause the mass to be raised to a higher point than would be possible otherwise. 25 In this form of the invention the inner ends of the ribs *B* are united by an annular closing member *b'*.

In Figs. 5 and 6 another embodiment of the invention is shown, in which the mill *a* is provided with circumferential rows of radially disposed flanges or thin flat blades *d* (as in Figs. 3 and 4) of a thickness only sufficient to give them the required strength and a radial length which will practically 30 engage the layer of grinding bodies and material on the ascending side of the mill. These rows of blades are disposed in continuous, parallel, circumferential series as described with respect to the plates or flanges 35 *b* and *b'*. The blades *d* permit the material to pass freely between them in its longitudinal movement through the mill, while exerting such frictional drag upon the material and grinding bodies that the material 40 and grinding bodies are carried up with the ascending wall of the mill in the manner hereinbefore described.

In the operation of the improved mill the material and grinding bodies lie between 50 the partitions at the bottom and, as the mill rotates are carried up with the wall of the mill beyond the point at which the centrifugal force is effective and to a point where gravity prevails, and thus travel in parallel, 55 transverse streams downward toward the opposite side of the mill, whereby the material is ground between the grinding bodies. During the operation of the mill the material and grinding bodies fall in streams in 60 the manner described and not in successive masses as would be the case where longitudinal ribs or corrugations are employed, and will not be tossed about in the mill in various directions as would be caused by irreg-

ularly spaced knobs and protrusions or 65 pockets on or in the wall of the mill, but will descend in parallel, transverse streams, and the material will therefore be ground uniformly and continuously. The partitions for assisting in the lifting of the mass are 70 not such as to interfere with the continuous movement of the material through the mill.

The ribs or flanges or partitions may be changed in form and number without departing from the spirit of this invention, 75 provided they are so shaped and disposed with respect to each other as to be effective in affording substantial frictional drag for the mass and carrying it to a point where an effective action of the grinding bodies on 80 the material will result.

I claim as my invention:

1. An improvement in the art of grinding in grinding mills which consists in producing in said mill a slowly rotating mass of 85 grinding bodies and material to be ground, applying closely related annularly arranged and extended frictional lifting ribs having surfaces extending in the direction of rotation to said mass while rotating and causing 90 a free longitudinal feeding of said mass at points below the inner surface of said rotating mass.

2. A grinding mill for grinding with free 95 grinding bodies provided with closely related series of parallel, circumferential annularly arranged and extended ribs along its inner wall, spaced from one another circumferentially to provide openings below the inner periphery of said ribs which ribs 100 serve to separate the charge into parallel, transverse streams, provide communicating channels between such ribs for free longitudinal feeding of the material and afford lateral support for the charge at the sides 105 of such streams.

3. A grinding mill for grinding with free 110 grinding bodies provided with closely related series of parallel, circumferential annularly arranged and extended ribs along its inner wall, which serve to separate the charge into parallel, transverse streams, said ribs being spaced from one another to provide substantially radially extended openings therebetween below the inner edge of 115 said ribs to increase the frictional drag of the lateral faces at the sides of said streams and permit free longitudinal feeding movement of the material in the mill.

4. A grinding mill for grinding with free 120 grinding bodies provided with closely related series of parallel, circumferential, annularly arranged and extended ribs along its inner wall, spaced from one another circumferentially to provide openings below 125 the inner periphery of said ribs which ribs serve to separate the charge into parallel, transverse streams, provide communicating

channels between such ribs for free longitudinal feeding of the material and afford lateral support for the charge at the sides of such streams, and an annular closing member united with said ribs at their inner ends and providing a free and unobstructed axial passageway.

This specification signed and witnessed this 10th day of April A. D., 1915.
